US00D837274S

(12) **United States Design Patent** (10) Patent No.: **US D837,274 S**
(45) Date of Patent: ** Jan. 1, 2019

(54) **MONITORING CAMERA**

(71) Applicant: **AXIS AB**, Lund (SE)

(72) Inventors: **Magnus Ainetoft**, Lund (SE); **Morten Bergstrom**, Lund (SE); **Mathias Walter**, Arlov (SE); **Mariano Vozzi**, Malmo (SE); **Daniel Ahman**, Lomma (SE); **Elin Carrander**, Bjarred (SE)

(73) Assignee: **AXIS AB**, Lund (SE)

(**) Term: **15 Years**

(21) Appl. No.: **29/630,052**

(22) Filed: **Dec. 19, 2017**

(57) **CLAIM**

The ornamental design for a monitoring camera, as shown and described.

DESCRIPTION

FIG. 1 is a perspective view of a monitoring camera showing our new design;

FIG. 2 is a right side view thereof;

FIG. 3 is a front elevational view thereof;

FIG. 4 is a top plan top plan view thereof;

FIG. 5 is a left side view thereof;

FIG. 6 is a bottom plan top plan view thereof; and,

FIG. 7 is a rear elevational view thereof.

The broken lines shown in the drawings depict portions of the monitoring camera and form no part of the claimed design.
